UNITED STATES PATENT OFFICE.

JAMES B. HYDE, OF ST. LOUIS, MISSOURI, ASSIGNOR OF ONE-HALF TO
ALVIN S. WARD, OF SAME PLACE.

BOILER-FEEDER.

SPECIFICATION forming part of Letters Patent No. 267,536, dated November 14, 1882.
Application filed August 12, 1882. (No model.)

To all whom it may concern:

Be it known that I, JAMES BOYD HYDE, of St. Louis, Missouri, have made a new and useful Improvement in Steam-Boiler Feeders, of which the following is a full, clear, and exact description, reference being had to the annexed drawings, making part of this specification, in which—

Figure 1 is a sectional elevation of the improved feeder. Fig. 2 is a sectional elevation taken at right angles to that of Fig. 1, and Figs. 3, 4 details.

The same letters denote the same parts.

I have heretofore, December 11, 1877, No. 198,113, obtained Letters Patent for an improved boiler-feeder by means of which the water can be supplied to the boiler without using a pump. The present feeder is an improvement upon the one referred to, in that it is automatic in its operation.

In the drawings, A represents the boiler; B, an inclosed tank above the water-line of the boiler; C, another inclosed tank above the tank B, and D a chamber above the tank C.

The chamber D is preferably inclosed. E E' represent a pair of vessels, attached by means of the arms e e to the shaft F. The shaft is journaled in the walls d d of the chamber D, and outside the walls the shaft is furnished with the cranks f f'. The shaft F, carrying the vessels E E', can be oscillated in its bearings, and so as to bring the vessels E E' alternately upward in an upright position above the shaft F and downward in a reversed position below the shaft F.

A pipe, G, leads from the boiler A to the tank C, an exhaust-pipe, H, leads from the tank C to the open air, a pipe, I, leads from the chamber D to the tank C, a pipe, J, leads from the tank C to the tank B, and a pipe, K, leads from the tank B to the boiler A. The feed-water is supplied through the pipe L.

The operation is as follows: The feed-water flows from the pipe L into the upper one of the vessels E E'. As shown in the drawings, it is the vessel E. The vessels E E' are shaped so that after being suitably filled with the feed-water they will become unbalanced, and in consequence cause the shaft F to turn in its bearings. To this end the vessels E E' may be shaped as shown in Fig. 1 more distinctly—

that is, be enlarged at the upper end, at one side of the center, as shown at E'. As the vessel E becomes filled in the part e', the shaft F turns, causing the vessel E to be carried downward below the shaft F and its contents to be discharged into the chamber D. As the vessel E is thus carried downward the vessel E' is carried upward and into the position previously occupied by the vessel E. The vessel E' is now filled and the operation repeated—that is, the vessel E' is carried downward, its contents discharged, and the vessel E brought upward again. The projection e' in the vessel E' is, when the vessel is above the shaft, on the opposite side to that on the vessel E. This causes the shaft F to oscillate and to move the cranks f f' accordingly. As the cranks f f' are thus moved reciprocatingly, they encounter the handles g g' and h h' of the valves g² and h² of the pipes G and H, respectively—that is, in the pipe G there is a valve, g², by means of which the flow of steam from the boiler to the tank C is regulated, and in the pipe H there is a valve, h², by means of which the exhaust 75 from the tank C is regulated. The valve g² has a two-arm handle, g g', and the valve h² has a two-arm handle, h h'.

The operation is as follows: As the shaft F turns one way the cranks f f' operate on the valves g² h² to close the pipe G and open the pipe H. The water then flows from the chamber D past the check-valve i in the pipe I into the tank C. As the shaft F turns back, the cranks f f' act to open the valve g² and close the valve h². The same steam-pressure then exists in the tanks C D as in the boiler, and the water flows from the tank C into the tank D, and thence into the boiler A. The water continuing to flow from the pipe L into the upper one of the vessels E E', the shaft F is turned again, and the operation of filling and emptying the tank C is repeated, and so on.

The arms e e are preferably furnished with extended surfaces e² e²—say in the form of a flat strip—for the purpose of gradually checking the movement of the vessels E E' in their alternating movement. The strips e² encounter the water in the chamber D, and thus gradually arrest the movement of the vessels. The water-line in the chamber D is indicated by the broken line d, Fig. 1. The rising of the

water above the level indicated is prevented by the overflow-pipe d' . The motion of the shaft F or the vessels E E' might be communicated to the valves $g^2 h^2$ in any suitable manner. I consider, however, the means shown the most desirable. The two positions of the handles $g g'$ or $h h'$ are shown in Figs. 3 and 4, respectively. Any suitable stop may be used for preventing the vessels E E' from rotating too far. The pipe L for this purpose may be extended at l to come in the way of the strips $e^2 e^2$, as shown. The water might flow from the tank C directly into the boiler A; but I prefer to have the water delivered first into the tank B, as shown. This last-named tank may be larger than the tank C, and sufficiently large to enable the water to accumulate there or to come under the influence of the heat of the steam of the boiler, and thereby become heated before entering the boiler. Should the water rise too high in the tank B, the ball-lever M acts through the connection m and valve m' to check the flow of water in the pipe L. The pipe J is provided with a valve, j , for closing the pipe J when desired. This valve j may be a check-valve seating upward, similar to the valve i in the pipe I.

I claim—

1. The combination of the chamber D, the shaft F, and the oscillating pair of vessels E

E', said vessels alternately receiving and discharging water, substantially as and for the purpose described.

2. The combination of the pipe L, the chamber D, the shaft F, and the vessels E E', as and for the purpose described. 35

3. The combination of the chamber D, the shaft F, the vessels E E', the cranks $f f'$, the valves $g^2 h^2$, and the pipes G H, substantially as described. 40

4. The combination of the chamber D, the shaft F, the arms $e e$, the vessels E E', and the strips $e^2 e^2$, substantially as described.

5. The combination of the chamber D, the shaft F, the arms $e e$, the strips $e^2 e^2$, and the stop l , substantially as described. 45

6. The chamber D, having the overflow-pipe d' , in combination with the oscillating pair of vessels E E', substantially as described.

7. The oscillating pair of vessels E E', having the enlargement e' , in combination with the chamber D, as and for the purpose described. 50

8. The combination of the chamber D, the oscillating shaft F, the cranks $f f'$, the valves $g^2 h^2$, having the two-part handles $g g' h h'$, and the pipes G H, substantially as described. 55

JAMES B. HYDE.
